UNITED STATES PATENT OFFICE

2,470,881

PORCELAIN-COATED GAS BURNER

George W. Zimbelman, Signal Mountain, Tenn.,
assignor to Samuel Stamping and Enameling
Company, Chattanooga, Tenn., a corporation of
Tennessee

Application December 17, 1945, Serial No. 635,521

1 Claim. (Cl. 158—116)

1

This invention relates to a gas burner.

A primary object of the invention is the provision of a gas burner wherein the manifold and burner housing is constructed of similar sections formed from relatively light gauge sheet steel, the sections being connected intermediate the top and bottom faces of the burner by a single weldless seam, and one of the sections being provided with a circular series of nozzles in the outer circumferential wall thereof and with the axes of the nozzles at a relatively small angle to the horizontal.

A further object of the invention is the provision of a gas burner including a manifold and a circular burner housing in communication therewith, the housing surrounding a control air admission opening and a circumferential series of elongated nozzles projecting from the outer wall of the housing at an angle of less than 45° to the horizontal.

A still further object of the invention is the provision of a gas burner constructed of relatively light gauge sheet steel having the inner and outer surfaces thereof inclusive of the burner ports enameled whereby the burner is neat in appearance as well as being self-cleaning in use.

Other specific objects, novel features of construction and improved results of the burner will appear in more detail in the following description when read in the light of the accompanying drawings.

In the drawings:

Fig. 1 is a top plan view of the burner constructed in accordance with a preferred embodiment thereof.

Fig. 2 is a side elevational view of the burner.

Fig. 3 is a vertical sectional view in the plane of line 3—3 Fig. 1 with the nozzles omitted.

Fig. 4 is an enlarged sectional view disclosing the press fit of a nozzle in the burner housing as well as the internal and external enamel finish.

Fig. 5 is an inside plan view of one of the burner sections.

Fig. 6 is a similar view of the other burner section.

Fig. 7 is a view of a flanged disc mounted on the free end of the manifold.

Referring now in detail to the drawings, B designates the burner in its entirety. The burner body is constructed of a pair of sheet steel sections 10 and 11 and an end cap or flanged disc 12.

Each of the sections is pressed from relatively light gauge sheet steel and each comprises a half manifold portion 13 and a half burner housing

2

portion 14 while section 10 is provided with a relatively wide marginal flange 15 and section 11 is provided with a similar but relatively narrow flange 16.

5 The flanges 15 and 16 extend from the free end of the manifold portions and encircle the housing portions and the flanges extend laterally of the edges of the cupped sections 10 and 11 forming the burner.

10 It is to be noted that the sections 10 and 11 are identical in form and size except for the different width flanges 15 and 16.

15 The sections 10 and 11 are assembled with the flanges 15 and 16 in face engagement and the wider flange 15 is turned downwardly and inwardly over the narrower flange 16 whereby providing a lock seam 17 in the absence of welding the sections together.

20 With the sections thus united a manifold m substantially circular in cross section is provided by portions 13 and a burner housing h is provided by the portions 14.

25 The burner housing h is circular in plan and comprises inner and outer side walls 18 and 19 merging into upper and lower curved walls 20 and 21 and the inner wall 18 defines a relatively large air opening 22.

30 The inner walls 18 of the sections 10 and 11 are provided with mating flanges 23 in the planes of flanges 15 and 16 and are made fluid tight by the seam 17 as well as the porcelain enamel applied as later described.

35 The flanges 23 are relatively narrow and circumscribe an opening 24 within the opening 22.

35 The manifold m communicates with the interior of the housing h and the axis of the manifold is at right angles to the axis of the housing and intersects same in the plane of the flanges 15 and 16.

40 The end cap 12 is provided with a central opening 25 for reception of a gas supply nozzle and is also provided with air admission openings 26. The cap includes a marginal flange 27 which frictionally engages the outer surface of the free end of the manifold m, and the cap is further retained in position by the applied porcelain enamel.

45 The section 10 is provided with a circumferential series of ports 28 in the outer wall thereof and which are provided prior to assembly of the two sections, and the section 10 may be further provided with a relatively small number (preferably three) of ports 29 in its inner wall or at the juncture of the inner and top walls.

50 A plurality of elongated nozzles 30 are pressed into the ports 28 and similar nozzles 31 are

pressed into the ports 29. The ports 28 and 29 are so disposed that the nozzles, particularly nozzles 30, project outwardly from the central opening 22 at an angle of substantially 30° or less to a horizontal plane.

This arrangement of the nozzles substantially eliminates the common and objectionable flash back in gas burners.

When the sections 10 and 11 together with cap 12 and nozzles 30 and 31 are assembled, the burner is immersed in a liquid porcelain enamel P (illustrated only in Fig. 4 for greater clarity in the other figures) whereby the exterior of the burner does not so readily collect dirt due to its smooth surface, and is easy to clean when dirt does collect. Furthermore, the interior of the burner including the nozzles is porcelain coated whereby the burner is substantially self-cleaning internally in the use thereof.

By immersing the burner in liquid enamel it is not only porcelain coated, but the heat used for baking is sufficient to properly anneal the sheet steel and thereby avoid any possible future warping thereof.

From the foregoing disclosure, it will be seen that a gas burner is provided which is not only capable of manufacture at relatively low cost, but which is also highly efficient in operation.

It is to be particularly noted that the relatively long nozzles arranged as disclosed prevent flash back in operation of the burner, and further provide for efficient operation with natural, manufactured gas, or liquefied petroleum gases.

By constructing the two sections 10 and 11 of like form the manufacture of the burner is materially facilitated, and by the provision of the interior porcelain coating the burner is substantially self-cleaning in operation.

While I have disclosed the invention in accordance with a single specific embodiment thereof, such is to be considered as illustrative only, and not restrictive, the scope of the invention being defined in the subjoined claim.

What I claim and desire to secure by U. S. Letters Patent is:

A gas burner comprising a burner housing circular in plan and a manifold communicating therewith, the housing and manifold being formed of relatively light gauge steel, the housing having a circumferential series of relatively long nozzles extending through a wall thereof and projecting therefrom both inwardly and outwardly thereof and tapering toward their inner ends, and the inner and outer surfaces of the housing, manifold and nozzles having a porcelain enamel coating.

GEORGE W. ZIMBELMAN.
